UNITED STATES PATENT OFFICE.

THOMAS B. STEPHENSON, JR., OF BRISTOL, CONNECTICUT.

DESIGN FOR A BADGE.

SPECIFICATION forming part of Design No. 33,045, dated August 7, 1900.

Application filed June 14, 1900. Serial No. 20,370. Term of patent 3½ years.

To all whom it may concern:

Be it known that I, THOMAS B. STEPHENSON, Jr., a citizen of the United States, residing at Bristol, in the county of Hartford and State of Connecticut, have invented and produced a new and original Design for a Badge, of which the following is a specification, reference being had to the accompanying drawing, forming part thereof.

10 The leading feature of my design is a brooch or pendant consisting of the figure of a man, blindfolded, seated backward upon a goat, and for support grasping with both hands the tail of the goat, substantially as shown in the accompanying drawing.

Having thus described my invention, what I claim as new, and desire to secure by Letters Patent, is—

15 The design for a badge, substantially as herein shown and described.

In testimony whereof I have signed my name to this specification in the presence of two subscribing witnesses.

THOMAS B. STEPHENSON, JR.

Witnesses:

ROGER S. NEWELL,
ALICE E. BROWN.
